(57) **CLAIM**

The ornamental design for a stuffed animal barrel-shape design, as shown and described.

DESCRIPTION

FIG. 1 is a top perspective view of stuffed animal barrel-shape design embodying my new design;

FIG. 2 is a bottom perspective view of the stuffed animal barrel-shape design embodying my new design;

FIG. 3 is a top plan view thereof;

FIG. 4 is a bottom plan view thereof;

FIG. 5 is a front elevational view thereof;

FIG. 6 is a rear elevational view thereof; and,

FIG. 7 is a side elevational view thereof, and the right side elevational view being a mirror image thereof.

The broken line showing is for illustrative purposes only, and forms no part of the claimed design.
